[57] CLAIM

The ornamental design for a flexible container for medical liquids, substantially as shown and described.

DESCRIPTION

FIG. 1 is a front perspective view of a flexible container for medical liquids, showing my new design;
FIG. 2 is a front elevation thereof;
FIG. 3 is a side elevational thereof;
FIG. 4 is a top plan view thereof;
FIG. 5 is a bottom plan view thereof;
FIG. 6 is a front perspective view similar to FIG. 1 but in a filled condition;
FIG. 7 is a front elevation thereof;
FIG. 8 is a side elevational thereof;
FIG. 9 is a top plan view thereof; and
FIG. 10 is a bottom plan view thereof.
